CODE DETECTING MEANS

Arthur L. Jerome, Edgewood, Pa., assignor to
Westinghouse Air Brake Company, a corpora-
tion of Pennsylvania

Application March 18, 1947, Serial No. 735,391

6 Claims. (Cl. 246—34)

1

My invention relates to coded signaling systems and particularly to improved means for detecting the code following operation of a contact employed in such systems.

In coded signaling systems, code following operation of a track or other relay having a contact recurrently operated between a first and a second position may be detected by means of a slow release relay and a condenser which are connected so that when the code following relay contact is in its first position, energy is supplied to the condenser, and when the code following relay contact is in its other position, the energy stored in the condenser is supplied to the winding of the slow release relay. As a result, when the contact of the code following relay is operating between its two positions in response to the supply of coded energy to the relay winding, the condenser is periodically charged and discharged, the energy at discharge being supplied to the winding of a slow release relay. This relay is selected so that its release time is longer than the time interval between the pulses of energy supplied from the condenser so that as long as the code following relay responds to coded energy the contacts of the slow release relay are picked up. If the code following relay contact should remain in its first position for a substantially long time interval, the condenser will be charged, but the circuit for supplying energy from the condenser to the winding of the slow release relay will remain interrupted, and after a time interval the contacts of the slow release relay will release. Similarly, if the code following relay contact should remain in its other position for a substantially long time interval, the condenser will be connected to the winding during the interval, but after the energy stored in the condenser has been dissipated in the winding of the slow release relay, the slow release relay will release its contacts.

From the foregoing it will be seen that the cessation of operation of the contact of the code following relay results in the release of the slow release relay. Circuits for the control of various functions may be established over contacts of the slow release relay.

If for any reason the movable contact of the code following relay should engage both of the associated stationary contacts at the same time, energy would be supplied directly to the slow release relay over the bridging contacts, and the circuits controlled over the contacts of the slow release relay might be improperly established.

It is an object of my invention to provide im-

2

proved code detecting means arranged so that defects in the contacts of the code following relay will not result in the improper energization of the code detecting means.

Another object of my invention is to provide improved means for detecting the code following operation of contacts which may be subject to misalignment, sticking, etc., that might cause the movable members of the contacts to simultaneously engage both of the associated stationary contacts.

Other objects of my invention and features of novelty will be apparent from the following description taken in connection with the accompanying drawing.

In practicing my invention, I provide an auxiliary code following relay, the contacts of which are picked up when and only when the contacts of the principal code following relay are in their first position, and a condenser which is supplied with energy from a suitable source of direct current by a circuit including a contact of the principal code following relay closed in its first position and a front contact of the auxiliary code following relay. When the contacts of the principal code following relay are in their second position and the contacts of the auxiliary code following relay are released, a circuit is established to supply the energy previously stored in the condenser to the winding of a slow release relay. If the contacts of the principal code following relay are defective so that they simultaneously engage both of the associated stationary contacts, the auxiliary code following relay will be picked up and its contact will interrupt the circuit for supplying energy from the condenser to the slow release relay to thereby insure that it remains released.

I shall describe one form of code detecting means embodying my invention, and shall then point out the novel features thereof in claims.

The accompanying drawing is a diagrammatic view of a section of railway track equipped with signaling apparatus employing code detecting means embodying my invention.

Referring to the accompanying drawing, there is shown therein a section of railway track having track rails 1 and 2, which are separated from the rails of the adjacent sections by the insulated rail joints 3. Traffic normally moves through this section from left to right, as indicated by the arrow. A signal S, which, as shown, is of the color light type having a green lamp G and a red lamp R, is located at the entrance end

of the section, and governs the entrance of traffic into the section.

A conventional type of coded track circuit is shown, including a coding device CT having a contact 10 which is recurrently operated between a first and a second position, and a track battery TB for supplying energy to the track section, the battery and coding device being located at the right-hand or exit end of the section. At the entrance end of the section, there is provided a code following track relay TR, an auxiliary relay TP of the code following type, a slow release relay HR, a rectifier K, and a condenser Q.

In addition, there is provided at each end of the section, a source of direct current energy, not shown, whose positive and negative terminals are designated B and C, respectively.

With the equipment in its normal condition as shown in the drawing, the coding device CT is continuously connected to terminals B and C of the source, and as a result, its contact 10 is recurrently operated at a selected rate, for instance, 180 times per minute. When the contact 10 of coding device CT moves to its second or closed position, the track relay TR is supplied with energy by the circuit which is traced from the positive terminal of battery TB, over front contact 10 of coding device CT, over section rail 1, through the winding of track relay TR and through section rail 2 to the negative terminal of battery TB. On the supply of energy to the winding of relay TR the relay contacts move from their first or released position to their second or picked up position. Accordingly, the movable contact 12 of relay TR is disengaged from its stationary back contact 14, and movable contact 16 of relay TR is moved into engagement with its stationary front contact 18. After a short time interval, the contact 10 of coding device CT moves to its first or released position, interrupting the supply of energy to track relay TR over section rails 1 and 2, and as a result, the movable contact 12 of relay TR is moved into engagement with its stationary back contact 14 and movable contact 16 of relay TR is disengaged from its stationary front contact 18.

It will be seen from the foregoing that the supply of impulses of energy to the winding of relay TR cause operation of the contacts 12 and 16 of relay TR. When the movable contact 12 of relay TR releases and engages stationary back contact 14, it establishes a circuit to supply energy to the winding of relay TP. This circuit is traced from terminal B, over movable contact 12 and stationary back contact 14 of relay TR, and through the winding of relay TP to terminal C. As a result relay TP is energized and its contact 20 is moved from its first or released position to its second or picked up position. Accordingly, movable contact 20 is moved out of engagement with its stationary back contact 22 and into engagement with its stationary front contact 24. A circuit is thereby established to supply energy to the condenser Q, which circuit is traced from terminal B, over movable contact 12 and stationary back contact 14 of relay TR, through the rectifier K, over stationary front contact 24 and movable contact 20 of relay TP, to the left-hand element of condenser Q, the right-hand element of condenser Q being connected to terminal C. As a result, a charge of energy is built up in the condenser Q.

When the movable contact 12 of relay TR is picked up and disengaged from its stationary back contact 14, the circuits previously traced for supplying energy to the relay TP and the con-

denser Q are interrupted. The energy stored in condenser Q may at this time attempt to flow through the circuit including movable contact 20 and stationary front contact 24 of relay TP and through the winding of relay TP to terminal C and thus to the right-hand element of condenser Q, but the rectifier K is poled so that energy cannot flow through it from the left-hand element of condenser Q, and as a result, the relay TP releases promptly on picking up of relay TR.

At this time the movable contact 16 of relay TR engages its stationary front contact 18, and a circuit is established for supplying energy from the condenser Q to the winding of the slow release relay HR. This circuit is traced from the left-hand element of condenser Q, over movable contact 20 and stationary back contact 22 of relay TP, and over movable contact 16 and stationary front contact 18 of relay TR, and through the winding of relay HR to terminal C and the right-hand element of condenser Q. As a result, contact 26 of relay HR is picked up and establishes the circuit for supplying energy to the green lamp G of the signal S.

When the movable contact 16 of track relay TR is out of engagement with its stationary front contact 18, the supply of energy from condenser Q to the relay HR is interrupted. However, relay HR is slow in releasing its contacts, and the relay is selected so that its release time will bridge the intervals between the supply of impulses to its winding as long as relay TR is operated by coded energy and contact 26 of relay HR will remain picked up at this time.

From the foregoing it will be seen that as long as track relay TR is responding to impulses of energy supplied from the exit end of the track section over track rails 1 and 2, the relay HR will be picked up, and signal S will display a green aspect, indicating "proceed."

I will now assume that a train enters the section proceeding from left to right. The wheels and axles of the train offer a low resistance path to the energy being supplied to the rails 1 and 2 from the exit end of the section, and as a consequence, the amount of energy received by track relay TR is insufficient for its operation. As a result, the movable contacts 12 and 16 of relay TR move to their first or released position and remain in that position as long as the train is in the section.

When relay TR releases the relay TP picks up and the supply of energy to relay HR from condenser Q is interrupted by the movable contact 16 of relay TR and also by movable contact 20 of relay TP, and after a short time interval, the contacts of relay HR release, interrupting the supply of energy to the green lamp G of signal S, and establishing the circuit for supplying energy to the red lamp R of the signal, indicating "stop."

When the train passes out of the section, impulses of coded energy are again supplied to the winding of the track relay TR and its contacts operate in accordance with the impulses of energy received. Each time the contacts of relay TR are in their released or first position, the auxiliary relay TP is picked up, and energy is supplied to the condenser Q, and when the contacts of relay TR are in their picked up or second position, relay TP is released and energy is supplied from the condenser Q to the relay HR. The supply of energy to the winding of relay HR picks up the contact of that relay, extinguishing the red lamp R of signal S and lighting the green

lamp G. The equipment is thus restored to its normal condition as previously described.

If for any reason the contacts of relay TR should remain picked up continuously, it will be seen that although the condenser Q is connected to the winding of relay HR continuously, the supply of energy stored in condenser Q will be dissipated in a short time and contact 26 of relay HR will release to thereby light the red lamp R of signal S.

My invention has a particular advantage in detecting defects in the contacts of the track relay TR which cause the movable contact 12 to engage its stationary back contact 14 at the same time the movable contact 16 engages its stationary front contact 18, and cause both contacts to remain in that position. If this condition arises, contact 20 of relay TP will be picked up and energy will be supplied to condenser Q. In addition contact 16 of relay TR will engage its stationary front contact 18 in the circuit for relay HR, but since contact 20 of relay TP is picked up, energy will not be supplied to relay HR, and its contact 26 will remain released to light the red lamp R of signal S.

It will be seen therefore that defects in the contacts of the relay TR cannot result in the improper display of a green or "proceed" aspect by signal S, but can only result in the display of the red or stop indication by this signal.

Likewise, any failure of the contacts of relay TP to operate as intended cannot result in improper energization of relay HR. If relay TP remains released when relay TR is released, energy will not be supplied to the condenser Q and on subsequent picking up of relay TR energy will not be supplied from the condenser to relay HR. Similarly, if when relay TR picks up the relay TP does not release energy will not be supplied from condenser Q to relay HR and it will remain released.

If the contacts of relay TP are defective so that movable contact 20 simultaneously engages its front contact 24 and its back contact 22, the relay HR will not be improperly energized. Under these conditions, if relay TR is steadily released energy will be supplied to condenser Q, but will not be supplied through contacts 24-20-22 of relay TP to relay HR since the circuit of relay HR is open at contact 16 of relay TR. If the relay TR is steadily picked up the circuit for supplying energy to condenser Q is open at contact 12 of relay TR and energy will not be supplied to the condenser, and will not be supplied through contacts 24-20-22 of relay TP to relay HR and it will remain released and maintain the circuit of the red lamp R.

From the foregoing it will be seen that the relay HR will not be improperly energized as a result of defects in the contacts of the code following track relay TR or of the code following auxiliary relay TP, but will remain released if such a condition arises.

Although I have herein shown and described only one form of code detecting means embodying my invention, it is understood that various changes and modifications may be made therein within the scope of the appended claims without departing from the spirit and scope of my invention.

Having thus described my invention, what I claim is:

1. In combination, a principal code following relay having contacts movable between a first and a second position in synchronism, an auxiliary

code following relay having first and second circuit closing means which are closed according as said auxiliary code following relay is deenergized or energized respectively, a slow release relay, an asymmetric unit, a condenser, a circuit including a first position contact of said principal code following relay for supplying energy to the winding of said auxiliary code following relay, a circuit including said first position contact of said principal code following relay and said second circuit closing means of said auxiliary relay in series with said asymmetric unit for supplying energy to said condenser, said asymmetric unit being poled so that energy will flow therethrough to charge said condenser, but cannot flow therethrough from said condenser, a circuit including said first circuit closing means of said auxiliary code following relay and a second position contact of said principal code following relay for supplying energy from said condenser to said slow release relay, and a circuit controlled by a contact of said slow release relay.

2. In combination, a principal code following relay having movable contacts which are operated in synchronism between a first and a second position, an auxiliary code following relay having first and second circuit closing means, circuit means for causing said second circuit closing means of said auxiliary code following relay to close when the contacts of said principal code following relay occupy their first position and to cause said first circuit closing means of said auxiliary code following relay to close when the contacts of said principal code following relay occupy their second position, a slow release relay, a condenser, a first circuit including a first position contact of said principal code following relay and said second circuit closing means of said auxiliary code following relay for supplying energy to said condenser from a source of direct current, a second circuit including a second position contact of said principal code following relay and said first circuit closing means of said auxiliary relay for supplying energy to said slow release relay from said condenser, means for preventing the energy stored in said condenser from discharging through the winding of said auxiliary relay, and a circuit governed by a contact of said slow release relay.

3. In combination, a first contact recurrently operated between a first and second position, a second contact which is operated to one or the other of two positions according as said first contact is in its first or second position, a third contact which is recurrently operated between a first and a second position in synchronism with said first contact, means for operating said first, second and third contacts in the manner described, a condenser, a first circuit including said first contact closed in its first position in series with said second contact closed in said one position for supplying energy from a suitable source to said condenser, means for preventing the energy stored in said condenser from discharging through said first circuit, a slow release relay, a second circuit including said third contact closed in its second position in series with said second contact closed in said other position for supplying energy to said slow release relay from said condenser, and a third circuit governed by the contacts of said slow release relay.

4. In combination, a first, a second, and a third movable contact each of which is movable between a first and a second position, means for recurrently operating said first and second con-

tacts in synchronism between their first and second positions, means for controlling the position of said third contact and effective when said first contact is in its first position to cause movement of said third contact to its second position and when said first contact is in its second position to cause movement of said third contact to its first position, a condenser, a source of direct current, a first circuit effective when said first contact occupies its first position and said third contact occupies its second position to supply energy from said source of direct current to said condenser, means for preventing the energy stored in said condenser from discharging through said first circuit, a slow release relay, a second circuit effective when said second contact occupies its second position and said third contact occupies its first position for supplying energy from said condenser to said slow release relay, and a circuit governed by a contact of said slow release relay.

5. In combination, a principal code following relay having first and second contacts which are alternately closed at a given code rate, an auxiliary code following relay having first and second circuit closing means which are closed according as said auxiliary relay is deenergized or energized, a slow release relay, an asymmetric unit, a condenser, a source of direct current, a first circuit including said first contact of said principal code following relay to connect said direct current source to a winding of the auxiliary code following relay to energize that relay, a second circuit including said second circuit closing means of said auxiliary relay and said asymmetric unit to connect said condenser in multiple with said winding of said auxiliary code following relay, said asymmetric unit being poled to permit said condenser to be charged from said source and to block the flow of current from said condenser through said winding of the auxiliary code following relay, and a third circuit including in series said first circuit closing means of said auxiliary code following relay and said second contact of said principal code following relay to connect said condenser to a winding of

8
said slow release relay for recurrently energizing the slow release relay at said given code rate by discharge pulses from the condenser.

6. In safety code detecting apparatus for detecting the recurrent operation of contacts which may be subject to sticking or fusing, in combination, a principal code following relay having first and second contacts which are alternately closed at a given code rate, an auxiliary code following relay having first and second circuit closing means which are closed according as said auxiliary relay is deenergized or energized, a slow release relay, a condenser, a source of direct current, a first circuit including said first contact of said principal code following relay to connect said direct current source to a winding of the auxiliary code following relay to energize that relay, a second circuit including said second circuit closing means of said auxiliary relay to connect said condenser in multiple with said winding of said auxiliary code following relay, means for preventing the energy stored in said condenser from discharging through the winding of said auxiliary code following relay, and a third circuit including in series said first circuit closing means of said auxiliary code following relay and said second contact of said principal code following relay to connect said condenser to a winding of said slow release relay, whereby said slow release relay becomes energized by pulses of energy supplied from said condenser when and only when said principal code following relay contacts and said auxiliary code following relay circuit closing means are recurrently operated in synchronism.
